ABSTRACT OF THE DISCLOSURE

A method and apparatus is disclosed for decorating concrete including a mould form having a flat base surface to which a paper pattern is attached with the pattern including a printed outline of a desired design and electrical conductors imprinted on the paper within the lines of the design for enabling attachment of individual explosive buttons to required portions of the pattern prior to the filling of the form with fresh concrete. Each explosive member comprises an individual button extending inwardly from the base surface of the form and which buttons are embedded in the concrete upon the hardening of the concrete; all the explosive buttons are simultaneously detonated after removal or loosening of the form to create a chiseled effect in the face of the form. Another aspect of the invention resides in strip members attached to the pattern to provide a groove in the concrete to define an outline of the design with the explosive means being positioned inwardly of the groove so that the effect of detonation of the explosive members is confined to the area inside the groove members.

This invention is in the field of decorative design formation in permanent structural members such as poured concrete or the like and is specifically directed to the provision of a decorative design having a hand-chiseled appearance.

Decorative designs have previously been incorporated in stone and concrete members by hand-chiselling or carving and, in the case of pre-poured concrete, by the construction of special design forms in which the concrete is poured. These expedients are relatively expensive and while a hand-chiseled design is highly desirable from an aesthetic point of view, the increased labor costs and the availability of skilled labor have frequently precluded the employment of such designs.

This invention enables the obtainment of a design in a concrete body or the like which has the outer appearance of a hand-chiseled or carved design, but which is easily formed by non-skilled labor at a minimum expenditure of time and effort. Moreover, a wide variety of designs can be formed using the same basic method by the employment of different patterns having a wide variety of designs, shapes and sizes.

Therefore, it is the primary object of this invention to provide apparatus and method for providing a design in a concrete body which has the appearance of a hand-carved or chipped design.

Obtainment of the object of this invention is enabled through the provision of a concrete form having a generally flat base surface to which a paper pattern is attached. The paper pattern includes a printed outline of the desired design along with electrical conductor means to which individual explosive elements are attached. Each individual explosive element comprises a button formed

2

of plastic and having an explosive cap mounted on the outer end of an upwardly extending stem with the lower end of the button comprising a base flange which is tacked into position by small nails or the like driven through the paper pattern into the wooden form. Each pattern includes visible instructions indicating the position in which the explosive buttons are to be located for the particular design. In addition, strip means are provided in the form of moulding strips which are attached to the pattern by small nails driven through the strips into the base surface of the form to define the design outline in a frame-like manner. The explosive buttons are positioned on the interior of the frame design inwardly of the moulding strips.

5 Liquified concrete or the like is poured into the mould following positioning of all of the explosive buttons and the outline defining strips and the mould is removed or loosened following setting of the concrete. Electrical voltage is applied to the circuit on the pattern to detonate 10 the individual explosive members simultaneously to create a chiseled effect in the area of the concrete body in which the explosive members are located. Indentations formed in the concrete body by the moulding strips define the outline of the design and confine the effect of the detonation 15 of the explosive members to the area inwardly of the strips.

The manner in which the instant invention achieves its objectives will be better understood when the following written description is read in conjunction with the attached drawings in which:

FIG. 1 is a perspective view of the base member of a concrete form to which the design pattern is attached;

FIG. 2 is a perspective view with parts removed illustrating the complete form filled with concrete with the 35 explosive design forming components being illustrated in position in the form;

FIG. 3 is a perspective view of a completed design formed by the inventive apparatus and method;

FIG. 4 is a sectional view taken along lines 4—4 of 40 FIG. 2;

FIG. 5 is a sectional view taken along lines 5—5 of FIG. 3;

FIG. 6 is a perspective view of an inverted explosive button employed in practice of the subject invention;

45 FIG. 7 is a perspective view of another type explosive button; and

FIG. 8 is a perspective view of yet another type explosive button.

Attention is initially invited to FIG. 3 of the drawings 50 which illustrates a poured concrete body 10 having a design in the form of a cross 12 which has the appearance of having been hand-chiseled in the facing surface 14 of the concrete body 10. This invention is directed to the method and apparatus for providing the design 12 in the manner shown in FIG. 3.

The first step in practice of the invention comprises the attachment of a paper pattern 16 to plywood sheet 18 which forms the bottom of a concrete form 19. Plywood sheet 18 includes an upwardly facing base surface 20 to which the pattern 16 is attached by adhesive, tacks, or any other convenient means.

Pattern 16 is provided with a printed outline 22 of the desired design, which in this case, happens to be a cross. In addition, pattern 16 includes pattern conductor elements 24 which can be of printed-circuit construction or which can be individual wire members adhesively se-

cured to the face of the pattern 16. Detonator contacts 26 are provided on the ends of the pattern conductors 24 as shown in FIG. 1 with the detonator contacts being connectable to a source of voltage for a purpose to become apparent hereinafter. In addition, pattern 16 includes printed circles or the like 28 which indicate the locations at which individual explosive elements in the form of individual explosive buttons 30 are to be positioned.

Each explosive button comprises a stem support generally designated 32 formed of plastic or the like and having an explosive cap 34 on one end and a base flange 36 on the other end. Base flange 36 is provided with first and second radially extending conductor strips 38 having their inner ends adjacent an axial bore 40 extending from the base flange upwardly to the explosive caps 34. Conductors 41 extend upwardly from the radial conductor strips through bore 40 for engagement with the explosive caps 34. The base surface of the flange 36 is normally protected by a removable protective label 44 as shown in FIG. 6 and which may, if desired, protect a self-sticking adhesive on the bottom of flange 36. Positioning holes 42 are provided adjacent the outer ends of the conductors 38 and extend through the base flange 36 for enabling the attachment of the explosive buttons 30 to the plywood sheet 18 by means of small tacks or brads in an obvious manner.

FIG. 6 illustrates an explosive cap 34 in the shape of the roughened half of a sphere while FIGS. 7 and 8 respectively illustrate explosive caps of different configuration which would be used for providing a different decorative effect in accordance with the design being formed and the nature of the material in which the design is to be formed. The explosive buttons 30 illustrated in FIGS. 7 and 8 are otherwise identical to the button illustrated in FIG. 6. It should be noted that the explosive cap is of conventional electrically detonatable material which can be varied in size or strength in accordance with the particular design.

In any event, explosive buttons 30 are positioned in the printed areas 28 on the pattern 16 by means of tacks or brads 48 passing through the apertures 42 and driven through the pattern 16 into the plywood sheet 18. Adhesive means can also be employed for attaching the buttons if desired. The position of the individual explosive buttons will obviously vary in accordance with the particular design to be formed. It should be noted that the buttons are positioned so that the radially extending conductor strips 38 each engage one, but not both, of the pattern conductor members 24.

Moulding strips 50 are positioned on the printed outline 22 in the manner shown in FIG. 2 so as to define the edge of the design being formed. All of the explosive buttons are mounted on the interior of the frame design defined by the moulding strip members 50 as is clearly shown in FIG. 2. The form 19 is then filled with fresh liquified concrete which is permitted to set in a well-known manner. Following setting of the concrete, the mould 19 is removed or loosened and the detonator contacts 26 are connected to a conventional selectively operable voltage source which is actuated to detonate each of the individual explosive buttons 30 simultaneously to provide the design 12 shown in FIG. 3. If the mould is not removed, but is merely loosened by loosening the form ties prior to detonation, the mould would contain all flying debris notwithstanding the fact that the blast would lift the mould away from the poured body. The detonation of the explosive button provides a hand-chiseled effect which is confined to the design framed by a groove 51 formed by moulding strips 50 in an obvious manner.

Numerous modifications and variations of the subject invention will occur to those of skill in the art; for example, a very coarse mesh, like a chickenwire pattern, of primer cord could be employed to create unusual

designs. It should also be understood that the term "concrete" as employed herein is used to designate a wide variety of structural material which can be poured and set in a form and is not strictly limited to concrete constructions per se. Therefore, the nature and scope of this invention is to be limited solely by the appended claims.

I claim:

1. A method of forming a design in a poured concrete body comprising the steps of positioning a plurality of explosive means in predetermined positions in a general outline of the design to be formed in the interior of an empty concrete form, filling said form with fresh concrete, permitting said concrete to set and detonating said explosive means so as to create the desired design.
2. The method of claim 1 additionally including the step of positioning a pattern having an outline of a desired design on a base surface of the form prior to the positioning of the explosive means in the form so that the pattern provides an indication of the location in which said explosive means is to be positioned.
3. The method of claim 2 wherein said explosive means is positioned on said pattern in contact with electrical conductor means and wherein said detonation of said explosive means is effected by the subsequent step of applying electrical voltage to said pattern conductor means.
4. The method of claim 2 additionally including the step of attaching strip elements to said base surface to define a framed outline of the desired design within the interior of said framed outline said explosive means is positioned so that the effect of detonation of said explosive means is confined to said interior of said framed outline.
5. The method of claim 4 wherein said explosive means is positioned upwardly a spaced distance from said base surface of said form.
6. The invention of claim 5 wherein said explosive means is positioned on said pattern means in contact with electrical pattern conductor means provided on the surface of said pattern and wherein said detonation of said explosive means is effected by the application of electrical voltage to said pattern conductor means.
7. The method of claim 4 wherein said explosive means is positioned on said form by the step of driving brads through openings in the explosive means into the form.
8. The means for forming a desired design in a poured concrete body comprising a form having a base surface, explosive means connectable to said base surface in general outline of said design prior to the filling of said form with fresh concrete, means for detonating said explosive means following the setting of concrete in the form for effecting formation of said design in the surface of the concrete formed by engagement with said base surface of the form.
9. The invention of claim 8 wherein said explosive means comprises individual explosive buttons.
10. The invention of claim 9 wherein said explosive buttons each comprise a stem support having an explosive cap on one end and a base flange on the other end with said base flange facing said base surface of the form.
11. The invention of claim 9 additionally including pattern means connected to said base surface with said pattern including a visible means for defining said design so that attachment of said design to said base surface enables correct positioning of said explosive buttons on said base surface.
12. The invention of claim 11 wherein said means for detonating said explosive buttons comprises button mounted electrical conductors extending between said explosive caps and said base flange and pattern conductor means on the surface of said pattern engaging said button mounted conductor so that voltage applied to said pattern

3,729,535

5

conductor means causes detonation of said explosive caps.

13. The invention of claim 12 wherein said stem support is a hollow plastic member.

14. The invention of claim 13 additionally including design defining strip means connectable to said base surface for defining the outline of the design with said explosive buttons being mounted interiorly of said strip means.
